UNITED STATES PATENT OFFICE.

CLIO B. YAW, OF ARLINGTON, NEW JERSEY, ASSIGNOR, BY MESNE ASSIGNMENTS, TO
REMINGTON TYPEWRITER COMPANY, OF ILION, NEW YORK, A CORPORATION OF
NEW YORK.

TYPE-WRITING MACHINE.

1,106,435.

Specification of Letters Patent.

Patented Aug. 11, 1914.

Application filed June 28, 1912. Serial No. 706,361.

To all whom it may concern:

Be it known that I, CLIO B. YAW, citizen of the United States, and resident of Arlington, in the county of Hudson and State of New Jersey, have invented certain new and useful Improvements in Type-Writing Machines, of which the following is a specification.

My invention relates to stencil or card writing mechanism for typewriting machines and its general object is to provide improved mechanism of the character specified.

More particularly one object of my invention is to provide an improved stencil or card container.

Another object is to provide improved stencil or card guiding and feeding mechanism.

Another object is to provide improved ribbon mechanism which promotes the visibility of the writing on a stencil sheet.

Another object is to provide full stroke devices in connection with stencil or card feeding devices.

Other specific objects will hereinafter appear.

To the above ends my invention consists in the features of construction, combinations of devices and arrangements of parts to be hereinafter described and particularly pointed out in the claims.

The preferred form of my invention is herein illustrated as applied to a No. 10 front-strike Remington typewriting machine, although the invention may be applied in whole or in part and with various necessary or desired constructional changes to other styles of writing machines.

In the accompanying drawings, Figure 1 is a fragmentary front elevation of the upper part of the No. 10 Remington typewriting machine embodying my invention, parts of the machine being shown in section. Fig. 2 is a corresponding rear view. Fig. 3 is a side elevation of said machine, parts being shown in section. Fig. 4 is a vertical front to rear central sectional view taken about centrally of the machine and illustrating certain of the stencil guiding devices as applied to said machine. Fig. 5 is a vertical front to rear sectional view taken on a plane indicated by the dotted line α in Fig. 2

and looking in the direction of the arrow at said line. Fig. 6 is a fragmentary perspective view of the floor or bottom plate of the stencil holder and its mounting. Fig. 7 is a fragmentary longitudinal sectional view of the ribbon spool or holder.

As appears especially from Figs. 1, 2 and 4 the main frame of the machine comprises a base 1, posts 2 and a top plate 3 supporting stationary rails 4 which coöperate through anti-friction balls 5 with the truck 6 of a platen carriage which further includes a platen frame or carrier comprising end bars 7 and a cross bar 8.

The platen frame supports a rotary platen 9 which preferably is of the usual construction except that as shown in Fig. 2 there is a central section or portion 10 which, instead of being of ordinary rubber composition, is of celluloid, this celluloid section replacing the usual rubber sheath, which however remains at the ends. In assembling the parts one of the rubber end portions is arranged on the usual wooden core and then the celluloid section is slipped on to the core and suitably secured in place, after which the other rubber end portion is put on. The central celluloid section provides a hard backing for the stencil sheets and co-operates with the types properly to cut and impress said sheets. I have found in practice that by providing a hard surface, such as celluloid, for coöperation with the ordinary types, satisfactory stencil cutting operations may be performed, so that if desired the usual needle pointed types employed in stencil work may be dispensed with.

The platen frame 7, 8 on which the platen 9, 10 is rotatably mounted is connected with the truck 6 by links 11, and is shiftable up and down thereon by devices comprising a key controlled shift rod or bar 12 which provides a track-way for a roller 13 journaled on the cross bar 8. Printing movements of the carriage and platen are controlled by a spring motor or drum and letter feeding devices not herein disclosed but which are of the ordinary style. Type bars 14, each provided with an upper and a lower case type, are journaled below the platen on a supporting segment 15 and are connected with printing key levers 16 by a train of devices comprising for each type bar a link

17, a lever 18 and a second lever 19. The actuation of each lever 18 causes its associate type bar to coöperate with the front face of the platen and also effects a letter feed movement of the carriage.

Referring to Figs. 1 to 3, 5 and 7, the box or container for the cards or stencil sheets comprises two vertical end plates 20 connected near their lower ends by cross bars 21, the cross bars and end plates being rigidly secured together by screws 22, thus forming a rigid frame. This frame is rotatably mounted on a rod 23 connecting the end bars 7 of the platen frame and secured 10 to rearward extensions of said end bars, said cross rod 23 being one of the regular parts of the platen frame. The body portions of the end plates are turned or bent outwardly at their tops providing a flaring mouth to 15 facilitate the introduction of stencil cards while forward of the mouth portions the plates 20 extend upward for purposes hereinafter described. The cross bars 21 support a floor plate 24 provided at its forward side 20 with a downwardly extending lip 25, said floor plate being provided near its rear edge with parallel slots 26 (Fig. 6) which receive headed screws 27, said screws engaging in the rear cross bar 21 and adjustably securing 25 the floor plate to its support. A front plate 28 is arranged between the end plates 20 and is provided at each corner with a forwardly turned ear 29, which ears are secured to upward extensions of the side plates by 30 screws 30. The end plates are provided with hubs 31 through which the platen frame rod 23 passes, the container thus being pivotally mounted at its rear on the frame rod 23. The forward ends of the end plates are provided with integral arms 32 which are 35 curved downward at the front side of the platen and rearward under the same and rest at their lower ends against the front face of the platen frame bar 8 which thus serves as an abutment or support. The weight of the container and the parts carried on and supported thereby assists to maintain said container in normal position with the arms 32 in contactive engagement 40 with the bar 8 as in Figs. 3 and 5. The container and the parts supported on it are adapted to be swung upward on the rod 23 as an axis, the movement being limited by the engagement of the ends of the arms 32 45 with the face of the platen, this movement being for the purpose, among others, of facilitating the adjustment of the ribbon hereinafter described. To assist in restoring the container to normal position and also to 50 maintain it in such normal position, a restoring spring 33 may be provided, said spring being coiled around the rod 23 at the left of the container and having one end engaged in the left-hand hub 31, the other end 55 being anchored to a collar 34 screwed to the

rod 23. At the opposite end of the container a second collar 35 is screwed to the rod 23, this collar 35 preventing sliding movement of the container along the rod in one direction, while the spring 33 and its collar 34 70 limit sliding movement in the opposite direction, this construction being clearly shown in Fig. 2. As appears in the front view, Fig. 1, the front plate 28 is provided with a series of parallel vertical slots 36 giving a view of 75 the cards in the container and lightening the same. Between the outermost pairs of these slots 36 there are secured to the front plate by screws 37 vertical retaining springs or detents 38 which extend downward and at 80 their lower ends curve rearward through slots 39 in the front plate, said springs being adapted to engage with the foremost of the stencil cards or sheets. These stencil cards or sheets, designated in the drawing as 40, 85 are or may be of the usual style comprising a rectangular frame of card board to which the stencil paper is pasted. These stencil cards are arranged in a pack within the container behind the front plate and resting on 90 the floor plate. The pack is constantly pressed forward toward the front plate by a follower or pressure device in the form of a plate 41 arranged within the stencil container between the side plates thereof and 95 resting on the bottom plate, said plate 41 being adapted to travel forward and rearward toward and away from the front plate 28. The follower plate 41 is provided with rearwardly extending ears 42 which are 100 pivotally connected at 43 to the forward ends of parallel links 44, said links extending rearward and being pivotally connected at 105 45 to upright arms 46 and 47. These arms are provided with hubs 48 which, as shown in Fig. 2, are secured by screws 49 to a sleeve or hollow rock shaft 50 which bears rotatably on the rod 23, the sleeve rigidly connecting the arms 46 and 47 and providing 110 with them a rocking frame for controlling the follower plate through the links 44. The rocking frame is confined between the end plates 20 which maintain it in proper position on the rod 23. The arm 47 extends upward out of the stencil container and is 115 provided with a lateral finger piece, handle or key 51 for swinging the rocking frame rearward and retracting the follower plate when a fresh pack of stencils is to be inserted in the container. A draw spring 52 120 (Figs. 1 and 2) is anchored at its forward end to a pin 53 projecting from the left-hand end plate 20, the rear end of said draw spring being hooked over a pin 54 which projects laterally from the arm 47. Said 125 spring tends constantly to draw the rocking frame forward and maintain the follower plate in spring pressed engagement with the pack of stencils which are thus compressed between the follower plate 41 and front plate 130

28. By reason of the pivotal mounting of the follower plate it adjusts itself readily and is thrust by the spring pressed links 44 into contactive engagement with the rear-
5 most stencil card throughout substantially its entire surface. The floor plate 24 is so set in respect of the front plate 28 that a narrow mouth or slot way 55 is provided between the lip 25 and the lower end of the front plate, this mouth being adjusted a width just sufficient to permit the easy passage downward therethrough of one stencil at a time.

It will be observed especially from Fig. 5
15 that the parts are arranged so that the stencil or card container overhangs or overlies the platen while the mouth or opening 55 is in substantial vertical alinement with the printing face of the platen. The friction
20 springs 38 coöperate with the lower end portion of the foremost stencil card that is to be ejected as appears from Fig. 5, and while readily yieldable when force is applied to eject the stencil, nevertheless prevent the
25 stencil from dropping down accidentally through the slot 55. Also the upper end portion of the middle part of the front plate is turned back to provide a ledge 28a which overlies the foremost two or three stencils
30 and prevents any upward displacement thereof which would tend to force them out of the stencil container.

Devices are provided for ejecting the stencils one at a time from the container, the
35 stencils being forced down through the slot 55 and located at the front side of the platen in position to receive the first line of writing by a single continuous movement. The stencil or card ejecting or feeding devices
40 are hand-controlled and comprise, as shown in Figs. 1 to 3 and 5, a gravity frame composed of parallel arms or members 56 and a comparatively heavy cross bar 57 which serves as a weight and to which said arms
45 are rigidly secured by screws 58. Said arms are provided at their inner faces with small rollers 59 to travel up and down over the front plate 28. The arms 56 also carry stop pins 60 extending laterally from their inner faces, said pins also coöoperating with the front plate. The arms 56 are formed with open slots 61 which fit over and embrace a traveling shaft 62, said shaft providing a vertically reciprocatory support or
55 carrier on which the gravity frame 56, 57 is pivotally mounted. The shaft or carrier 62 is horizontally arranged in front of the plate 28 and is reduced at its ends as indicated at 63, the reduced ends engaging in
60 vertical guide slots 64 cut in the forward and upwardly extended portions of the end plates 20. Small pinions 65 are secured to the shaft 62 near its ends, said pinions meshing with rack sections 66 which are vertically arranged at the sides of the front plate

28 and are suitably secured thereto, the construction being such that the traveling shaft 62 is forced to travel evenly and skewing of it and also of the gravity frame is prevented. The cross bar or rod 57 tends because of gravity to swing forward on the shaft 62 as an axis and to force the lower ends of the arms 56 rearward toward the stencils through vertical slots 67 cut in the front plate 28 just inside the rack sections 66. 70 This rearward movement of the arms is limited by the rollers 59 contacting with the front plate 28 at the inner sides of the slots 67. Accidental displacement of the gravity frame from the shaft 62 by forcing the rod 57 rearward over the shaft is prevented by the coöperation of the stop pins 60 with the front plate. The construction is such that the gravity frame is loosely hung or mounted on the traveling shaft 62 and may swing freely thereon within limits but is prevented from undue movement as described. The lower ends of the arms 56 are flat and are normally horizontal, so that these ends are adapted for ready engagement with the stencil cards. The movements of the gravity feeding device 56, 57 are controlled by an actuator or hand lever 68 provided with a hub portion 69 which bears on a screw pin 70 projecting laterally from an ear on the 95 left-hand end plate 20. The lever 68 has a downward extension or tail piece 71 having a pin 72 at its lower end over which is hooked a draw spring 73, said spring extending forward parallel with the spring 100 52 and being anchored to the pin 53. The lever 68 normally inclines forward and upward at the left of the stencil container, the forward end of said lever turning upward and being provided with a finger piece or 105 key 74 which normally projects above the container and to the left of the same where it may be readily grasped and operated. The lever 68 is formed with an elongated slot 75 which engages a flanged roller 76, as 110 clearly shown in Fig. 1, said roller bearing rotatably on the reduced left-hand end 63 of the shaft 62, said end being extended leftward and threaded to receive a hexagonal nut 77 which confines the roller 76 to its 115 bearing and also prevents lateral displacement of the lever 68. Acting through said lever the spring 73 maintains the shaft 62 at the top of the guide slots 64 and restores said shaft and the gravity frame to the uppermost position after actuation. When the parts are in the normal position the lower ends of the arms 56 are swung rearward through the slots 67 to the limit of their movements and overlie the upper edge of 120 the foremost stencil card 40 near its ends. When a stencil card is to be ejected the key or finger piece 74 is forced downward to the limit of its movement as shown in Fig. 5, this limit being determined by the engage- 130

ment of the ends of the shaft 62 with the bottoms of the guide slots 64. The actuation of the lever 68 operates to force the shaft 62 downward, said shaft turning on its axis 5 as it moves bodily downward by reason of the intermeshing pinions and racks 65, 66 and carrying bodily with it the gravity frame 56, 57, the rollers whereof travel over the face of the front plate 28. The ends 10 of the arms 56 engaging with the foremost stencil card will, as the gravity frame moves downward, force said card to move continuously down through the slot 55 until it reaches the position shown in Fig. 5 in 15 which position it is adapted to receive the first line of writing. It will be observed that at this time the upper end of the stencil card is still within the slot 55 so that during subsequent line spacing movements 20 in writing the stencil the card will return upward step-by-step through the slot 55. At the end of the ejecting operation, the lever 68 is released, and as the ejecting device returns upward under the control of the 25 spring 73 the rear lower ends of the arms 56 will slide over the front of the side portions of the next stencil card now at the front of the container. As soon as said arms are lifted above the upper edge of said card, 30 said arms will swing back from the force of gravity acting through the weight or rod 57. This swinging movement carries the lower ends of the arms backward over the top of said stencil card and in position to 35 engage with it during the next ejecting operation.

The line spacing or upward movements of the stencil are caused by feeding devices which coöperate with the platen when the 40 platen is line spaced by the usual line spacing devices comprising ratchet wheel 78 and hand actuated pawl 79 (Fig. 2). Said stencil feeding devices comprise rollers 80, preferably of metal, which coöperate with 45 the rubber portion of the platen beyond the ends of the central celluloid portion 10, as is clear from Fig. 1. The feed or pressure rollers 80 are pivotally supported in carriers 81 which in turn are pivoted on and 50 depend from a cross rod 82 secured at its ends by screws 83 to the lower front portions of the end plates 20. The carriers or swinging arms 81 may turn freely on the rod 82 but are prevented from endwise movement 55 by collars 84 which are secured to said rod and maintain the arms 81 close to the lower ears 29. Draw springs 85, one anchored to the pin 53 and the other to a corresponding pin 53* on the right-hand plate 20, hook over 60 pins 86 projecting laterally outward from the arms 81 and exert a sufficient pressure upon the rollers 80 to feed the stencil upward in line spacing direction when the platen is turned by actuation of the pawl 79. 65 Usually there are three lines written on each

stencil card a unit's distance apart, and the parts are so proportioned in the present instant that when the partly ejected stencil card has been retracted or spaced upward three units' distances from the position shown in Fig. 5, its upper edge will be in register with and contiguous to the lower edge of the next stencil to be ejected. This next stencil will now be in register with the slot 55, it being understood that as soon as 70 the first stencil was ejected past the floor plate 24 the remainder of the pack in the container was forced forward by the spring pressed follower plate 41. The result will be that on the next downward actuation of 75 the actuator 68 the second stencil card will be ejected from the container and during its ejection will force the underlying written stencil sheet down out of the machine over guiding devices next to be described. It will be understood that after the first operation, then, of the actuator each subsequent operation will have the effect of forcing a written stencil out of the machine and of positioning the next succeeding stencil in position 80 to receive the first line of writing at the front of the platen.

Guiding devices over which the written stencil cards pass out of the machine are clearly illustrated in Figs. 1, 4 and 5 and comprise a plate 87 which is preferably of a light material such as aluminum, said plate being provided with ears 88 which are secured to the sides of the top plate forward of the platen by screws 89, washers 90 being 95 preferably interposed between the heads of the screws and the ears 88. The plate 87 is preferably of about the width of the type basket at its upper end, this width being sufficient to allow for endwise movements of the stencil from one side to the other. Said plate 87 extends from slightly in front of the platen downward over the rear of the type segment, inclining toward the rear of the machine and terminating just back of the base 1. The guide plate 87 narrows as it approaches the rear and its sides are turned up somewhat as indicated at 91 so that the plate forms a shallow trough or chute. A continuation 92 of the guide plate 100 87 may be made separate, if desired, said continuation being U-shaped in cross section as shown in Fig. 4 and being secured to the rear of the base by screws 93. The lower end of the guide plate or chute 87 preferably 105 overlaps the upper end of the plate 92 and the overlapping portions receive the screws 93 which thus secure the lower end of the plate 87 and its continuation 92 in place. The continuation 92 is of a width fore and aft sufficient to accommodate the stencils as they slide down over the chute 87 and rest on the bottom of the plate 92 which has no 110 ends nor top, so that the stencils may readily be removed. There is thus provided a guide 115 120 125 130

comprising two portions 87 and 92, the sides of which are in planes at right angles to each other.

In prior constructions it has been difficult 5 during the course of the writing to see clearly what has been printed on stencil cards, the impressed letters being hard to decipher unless the stencil cards were removed and held against the light. Consequently 10 mistakes in the writing are sometimes not detected until the stencils have been written and removed from the machine. In order to overcome this objection I provide a ribbon which is arranged behind the stencil card, 15 when the latter is in writing position, said ribbon being interposed between the stencil card and the platen. In the course of the writing the ribbon offsets on the back of the stencil and clearly outlines the characters 20 as they are printed, thus providing a sort of indicator for the printing.

The ribbon aforesaid, designated herein by the numeral 94, is controlled by novel feeding devices now to be described. Said ribbon is preferably of a width corresponding 25 to the length of the stencil platen 10 and is stored in roll form on a holder, carrier or spool comprising a hollow hub portion 95 and flanges 96 (Fig. 7). The spool is arranged at the rear of and above the platen, being supported on the rocking frame 46, 47, 50. One end of said spool is connected to and supported on a stud shaft 97 which bears in a boss or hub 98 rigid on the arm 30 47. The end of the hub 95 adjacent the shaft 97 projects outward beyond the flange and fits over the end of the stub shaft, being provided with a notch or slot 99 which engages a pin 100 on the shaft, thus connecting the parts so that they are compelled 35 to rotate together. A cap 101 is arranged outside the boss 98 and secured to the shaft by a screw 102, said cap assisting to prevent displacement of the shaft. The opposite 40 end of the spool core 95 fits over the inner end of a shaft 103 having a reduced portion 104 threaded at its end and provided with a thumb nut 105. The reduced portion 104 of the shaft bears in a bushing 106 secured 45 in a hub or boss 107 fixed to the arm 46, the inner enlarged end portion of the shaft 103 bearing directly in the boss.

Arranged between the portion 103 and the bushing 106 is a compression spring 108, said spring surrounding the reduced portion 104 and tending constantly to press the shaft inward toward the spool, this movement being limited by a flange 109 on the shaft. By pulling outward on the thumb nut or finger 50 piece 105, the spring 108 is overcome and the shaft 103 may be withdrawn from the spool which may then be readily detached from its supports. An automatic rotary movement 55 is given the spool to feed the ribbon by devices comprising a ratchet wheel 110

which is rigid on the shaft 97 (Figs. 2, 3 and 5.) Coöperative with the teeth of said ratchet wheel at the under side thereof is a feeding pawl 111 pivoted at 112 to the inner face of the left-hand end plate 20 and maintained in engagement with the ratchet wheel 110 by a spring 113 coiled around a boss 114 in which the pivot screw 112 is secured, said spring 113 bearing on the pawl 111 and constantly pressing it upward. The upward 70 movement of the pawl is limited by a tail piece 115 which contacts with the rear cross bar 21, the floor plate 24 being notched out as indicated at 116 to permit of this contractive engagement. The hub 48 of the arm 75 47 is cut away as indicated at 117 (Fig. 5) to permit of downward swinging movements of the pawl 111 to a limited extent. A coiled spring 118 is arranged on the shaft 97 between the ratchet wheel 110 and the arm 47 80 and not only serves to maintain the shaft 97 pressed inward with the head of the screw 102 against the cap 101 but also serves as a friction spring to prevent accidental or abnormal turning movements of the ribbon 85 spool. The ribbon is drawn off from the rear under side of the roll of ribbon 94 as appears from Fig. 5, the unwound portion passing forward under the stencil container 90 and being supported on and guided by a 95 guide plate 119, said guide plate being coiled around the sleeve 50 and pivotally supported thereby, said guide plate extending forward and its free end resting loosely on the top of the platen. The ribbon 94 100 passes from the guide plate down over the front side of the platen and between it and the stencil card that is positioned for writing, the loose or free end of the ribbon passing out at the rear of the machine over the 105 guide plate 87.

It will be observed that the pawl 111 is pivoted to a relatively fixed part, *i. e.*, the stencil container itself, while the ratchet wheel 110 and the ribbon spool are mounted 110 on the rocking frame comprising the sleeve 50 and the arms 46 and 47. The construction is such that when the finger piece 51 is pulled back to retract the follower plate and enable a new pack of stencil cards to be inserted, the ratchet wheel will move bodily. Since, however, the pawl 111 remains stationary and engaged between two of the teeth of the ratchet wheel, said ratchet wheel will be subjected to a rotary movement on 115 its longitudinal axis as well as a bodily swinging movement on the axis of the shaft 50. This rotary movement will be transmitted through the slot 99 and pin 100 to the ribbon spool and the ribbon, unwinding 120 the ribbon to a corresponding extent, in the present instance about one-eighth of an inch. The parts are proportioned so that each 125 time the follower plate is retracted from the front plate to its full extent, the ratchet 130

wheel 110 will turn to the extent of a single tooth. The rearward movement of the follower plate is limited by pairs of stop pins 120 which project inward oppositely from the end plates 20. The arm 47 is cut out at its forward edge as indicated at 121 so that the forward movement of the follower plate will not be obstructed by the engagement of the arm 47 with the upper left-hand limiting pin 120, the notch permitting the follower plate to be forced into contact with the front plate 28 by the spring 52 when all of the stencil cards have been ejected. As the follower plate advances intermittently during the stencil ejecting operations, the pawl 111 will slide inactively over the teeth of the ratchet wheel 110 which will not turn on its axis to feed the ribbon, but the ribbon spool will advance bodily with the rocking frame and the unwound portion of the ribbon will also advance correspondingly. Both the ribbon spool and ribbon will be retracted to the same extent when the follower is retracted.

From what has been said it will be understood that the ribbon is fed off the spool a unit distance each time a pack of stencils is introduced into the machine; that each card will be written on a different part of the ribbon due to the bodily forward movement of the ribbon spool; and that the same portion or section of the ribbon used with one stencil pack is also used with the next pack except for the one-eighth portion advanced permanently below the printing line when the follower is retracted and the spool turned axially. The capacity of the present device is some twenty-four or twenty-five stencil cards so twenty-four or five lines or a multiple thereof may be written between axial turning movements of the spool. The ribbon is used until practically exhausted, so that when said ribbon is fed down and back out of the machine it is used up and useless and may be cut off at intervals and thrown away. When the ribbon roll is completely exhausted a fresh ribbon may be applied to the ribbon spool. It will be understood that it is not necessary that the ribbon should make perfect impressions on the back of the stencil card but only that enough ink should be supplied to enable the character printed to be read easily through the stencil, this ink, of course, not being of any service subsequently in reproducing the impressions cut in the stencil card.

In order to insure that the lever or actuator 68 may be actuated to the fullest extent in ejecting the stencil cards, I may provide devices in the nature of "full stroke" devices which may comprise a pawl 122 pivoted at 123 to the extension or ear 20^a behind the pivot 70 (Fig. 3). Said pawl is maintained in its intermediate or central

horizontal position by a two-arm spring 124 secured to the inner face of the ear 20^a at 125, the free ends of said spring being bent outward over the top and bottom edges of said ear and engaging with the sides of the pawl 122 forward of its pivot. An extension or finger 68^a preferably integral with the lever 68 projects rearward from the pivot 70 and is provided at its ends with notches 126 which are adapted to coöperate with the pawl 122 when the lever 68 is swung downward. If the lever 68 is swung down to its fullest extent the finger 68^a will swing upward past the pawl which, after the passage of the finger, will return to its normal central position; but if the stroke of the lever 68 should not be completed, then the pawl will be left in engagement with one of the notches 126 and will thereupon coöperate with the finger 68^a to hold the lever 68 in the position in which it is left when the operator fails to complete the stroke to its full extent. The operator is thus notified that the stroke has not been completed, and needs only further to depress the key and the lever 68 to the limit of its movement to release the finger 68^a from the control of the pawl 122. During the return movement the pawl will be forced downward from its intermediate position to permit the finger 68^a to swing past it.

It will be observed that the stencil or card and associate devices are mounted on a shiftable platen frame or carrier so that the container shifts with the platen, enabling both the capitals and small letters to be printed on a stencil sheet.

It is to be understood that the invention is adapted for use with forms of work sheets other than stencil cards, and that various changes may be made within the spirit and scope of said invention.

What I claim as new and desire to secure by Letters Patent, is:—

1. In a typewriting machine, the combination of a platen carrier, a platen thereon, and a card container overhanging said platen and pivotally supported on said platen carrier and provided with arms which rest against an abutment on said platen carrier, said container being supported independently of the platen.

2. In a typewriting machine, the combination of a platen; a platen carrier comprising two cross rods or bars; and a card container loosely pivoted on one of said rods or bars and having portions bearing against the other rod or bar, said container being wholly supported independently of said platen.

3. In a typewriting machine, the combination of a platen; a platen carrier comprising a rod or bar at the rear of the platen and a second rod or bar below the platen;

and a card container loosely pivoted on said first named rod or bar and extending forward over the platen frame, said container being provided with downwardly extending 5 arms which abut against the second named rod or bar, said container being wholly supported independently of said platen.

4. In a typewriting machine, the combination of a platen; a platen carrier comprising a rod or bar at the rear of the platen and a second rod or bar below the platen; and a card container comprising arms curving downward at the forward and under sides of the platen and adapted to engage 10 with said second named rod or bar through the force of gravity, said container being wholly supported independently of said platen.

5. In a typewriting machine, the combination of a platen; a platen carrier comprising a rod or bar at the rear of the platen, and a second rod or bar below the platen; and a card container pivoted on said first named rod or bar and extending forward 25 over the platen frame, said container being provided with downwardly extending arms which abut against the second named rod or bar; and a spring for assisting to maintain 30 said arms in contactive engagement with the rod or bar against which they rest.

6. In a typewriting machine, the combination of a platen; a platen carrier comprising a rod or bar at the rear of the platen, and a second rod or bar below the platen; a 35 card container loosely pivoted on said first named rod or bar and extending forward over the platen frame, said container being provided with downwardly extending arms which abut against the second named rod 40 or bar; and means for preventing endwise movement of said container on said platen carrier, said container being wholly supported independently of said platen.

7. In a typewriting machine, the combination of a platen; a platen carrier comprising a rod or bar at the rear of the platen, and a second rod or bar below the platen; and a card container pivoted on said first named rod or bar and extending forward 50 over the platen frame, said container comprising end plates, cross bars connecting said end plates, a front plate, and an adjustable floor plate providing with the front plate a mouth for the cards, said end plates 55 being provided with hub portions which bear on the first named rod or bar and also having curved arms curving downwardly at the front and under sides of the platen and contacting with said second named rod 60 or bar.

8. In a typewriting machine, the combination of a platen, a card container, a follower for the cards in said container, a rocking frame, and links connecting said rocking

frame with said follower, said links being 65 relatively movable in respect both to said rocking frame and said follower.

9. In a typewriting machine, the combination of a platen, a card container, a follower for the cards in said container, a rocking 70 frame, parallel links connecting said follower with said rocking frame, and a spring constantly operative on said frame, said links being relatively movable in respect both to said rocking frame and said follower. 75

10. In a typewriting machine, the combination of a platen, a card container, a follower for the cards in said container, a rocking frame, parallel links connecting said follower with said rocking frame, a spring constantly operative on said frame, and a key 80 for manually controlling said rocking frame and said follower.

11. In a typewriting machine, the combination of a platen, a card container, a vertically arranged follower for the cards in said container, a rock shaft, crank arms on said rock shaft, and parallel links pivoted to said 85 crank arms and also pivoted to said follower. 90

12. In a typewriting machine, the combination of a platen, a card container, a vertically arranged follower for the cards in said container, a rock shaft, crank arms on said rock shaft, said rock shaft and crank 95 arms constituting a rocking frame, spring means constantly operative on said frame, and parallel links pivotally connected to said crank arms and to said follower.

13. In a front-strike typewriting machine, the combination of a platen, a card container above the platen, a vertically arranged follower for the cards in said container, a rock shaft, crank arms on said rock shaft, said 100 rock shaft and crank arms constituting a 105 rocking frame, a spring constantly operative through said frame to press said cards forward over the platen, and a key for controlling said rocking frame and said follower.

14. In a typewriting machine, the combination of a platen, a card container, a vertically arranged plate engaging the cards in said container, a rock shaft, crank arms on said rock shaft, said rock shaft and crank 115 arms constituting a rocking frame, a spring constantly operative on said frame, parallel links pivotally connected to said crank arms and to said plate, and a controlling key on one of said crank arms. 110 120

15. In a typewriting machine, the combination of a platen, a card container, a key controlled traveling shaft, means for positively compelling said shaft to turn on its axis during key controlled traveling movements and an ejecting device pivotally mounted on said shaft. 125

16. In a typewriting machine, the combi-

- nation of a platen, a card container, a key controlled traveling shaft, means for positively compelling said shaft to turn on its axis during key controlled traveling movements and a gravity ejecting device movably supported on said shaft.
17. In a typewriting machine, the combination of a platen, a card container, a traveling rod or shaft, means comprising rack and pinion devices for positively preventing skewing of said rod or shaft, and an ejecting device mounted on said rod or shaft.
18. In a typewriting machine, the combination of a platen, a card container, a traveling rod or shaft, means comprising rack and pinion devices for positively preventing skewing of said rod or shaft, and a gravity card ejecting frame mounted on said rod or shaft.
19. In a typewriting machine, the combination of a platen, a card container, a traveling rod or shaft, means comprising rack and pinion devices for positively preventing skewing of said rod or shaft, a gravity card ejecting frame mounted on said rod or shaft, and manual means for controlling said rod or shaft.
20. In a typewriting machine, the combination of a platen, a card container, a traveling rod or shaft, means for positively preventing skewing of said rod or shaft, a gravity actuated card-ejecting frame mounted on said rod or shaft, and a hand lever having a loose connection with said shaft.
21. In a typewriting machine, the combination of a platen; a card container; a traveling rod or shaft; means for positively preventing skewing of said rod or shaft; a gravity actuated card - ejecting frame mounted on said rod or shaft; manual means for controlling said rod or shaft, said manual means comprising a hand lever having a loose connection with said shaft; and a releasing spring connected to said hand lever.
22. In a typewriting machine, the combination of a platen; a card container; a traveling rod or shaft; means for positively preventing skewing of said rod or shaft; a gravity actuated card - ejecting frame mounted on said rod or shaft; manual means for controlling said rod or shaft, said manual means comprising a hand lever having a loose connection with said shaft; and full stroke devices associated with said hand lever.
23. In a typewriting machine, the combination of a platen; a card container; a traveling rod or shaft; means for positively preventing skewing of said rod or shaft; a gravity actuated card - ejecting frame mounted on said rod or shaft; a hand lever having a loose connection with said shaft; and full stroke devices associated with said hand lever, said full stroke devices comprising a series of notches on said hand lever, and a coöperative spring controlled pawl.
24. In a typewriting machine, the combination of a platen, a card container, a key controlled traveling shaft, pinions on said shaft, racks with which said pinions coöperate, and a card ejecting member connected to said shaft.
25. In a typewriting machine, the combination of a platen, a card container, a key controlled traveling shaft, pinions on said shaft, racks with which said pinions coöperate, guiding devices for said shaft, and a card-ejecting member supported on said shaft.
26. In a typewriting machine, the combination of a platen; a card container; a key controlled traveling shaft; pinions on said shaft; racks with which said pinions coöperate; guiding devices for said shaft; and a gravity frame comprising arms pivoted on said shaft and a cross bar connecting said arms.
27. In a typewriting machine, the combination of a platen; a card container; a traveling shaft; pinions on said shaft; slotted guide members for said shaft; racks rigid with said slotted guide members and coöperative with said pinions; a card - ejecting frame mounted on said shaft, said frame comprising arms pivoted on said shaft and provided with rollers, and a cross rod or bar connecting said arms; and relatively fixed guides, said rollers coöperating with said fixed guides and said arms projecting through slots in said last named guides.
28. In a typewriting machine, the combination of a platen; a card container; a traveling shaft; pinions on said shaft; slotted guide members for said shaft; racks rigid with said slotted guide members and coöperative with said pinions; and a card-ejecting frame mounted on said shaft, said frame comprising arms pivoted on said shaft and provided with rollers, and a cross rod or bar connecting said arms; slotted guides, said rollers coöperating with said guides and said arms projecting through the slots therein, said arms also being provided with limiting pins coöperative with said last named slotted guides.
29. In a typewriting machine, the combination of a platen; a card container; a traveling shaft; pinions on said shaft; slotted guide members for said shaft; racks rigid with said slotted guide members and coöperative with said pinions; a card - ejecting frame mounted on said shaft, said frame comprising arms pivoted on said shaft and provided with rollers, and a cross rod or bar connecting said arms; relatively fixed guides, said rollers coöperating with said fixed guides and said arms projecting through

slots in said last named guides; and a hand lever loosely connected with said shaft.

30. In a typewriting machine, the combination of a platen; a card container; a traveling shaft; pinions on said shaft; slotted guide members for said shaft; racks rigid with said slotted guide members and coöperative with said pinions; a card-ejecting frame mounted on said shaft, said frame comprising arms pivoted on said shaft and provided with rollers, and a cross rod or bar connecting said arms; relatively fixed guides, said rollers coöperating with said fixed guides and said arms projecting through 10 slots in said last named guides; a slotted hand lever; and connections comprising a roller mounted on said shaft and engaging with the slot in said hand lever.

31. In a front-strike typewriting machine, the combination of a platen, a card container overlying the platen and provided with a mouth in substantial alinement with the front face of the platen, means for supporting the card container in rear of the platen 25 and also under the platen, means for ejecting the cards one at a time downward through said mouth, and feeding devices coöperative with the front face of the platen, the operation of said feeding devices pressing said container against the supporting means that is under the platen.

32. In a front-strike typewriting machine, the combination of a platen, a card container overlying the platen and provided with a 35 mouth in substantial alinement with the front face of the platen, means for supporting the card container in rear of the platen and also under the platen, means for ejecting the cards one at a time downward 40 through said mouth, and pressure rollers coöperative with the front face of the platen, the actuation of said pressure rollers to feed a card downward also causing said container to be pressed against the supporting means that underlies the platen.

33. In a front-strike typewriting machine, the combination of a platen, a card container overlying the platen and provided with a mouth in substantial alinement with the 50 front face of the platen, means for ejecting the cards one at a time downward through said mouth, and card feeding devices coöperative with the front face of the platen and comprising pressure rolls, carriers on which 55 said pressure rolls are supported; a rod on the card container from which said carriers depend, and springs connected to said carriers and to said container.

34. In a front-strike typewriting machine, the combination of a platen, a card container overlying the platen and provided with a mouth in substantial alinement with the front face of the platen, means for ejecting the cards one at a time downward through

said mouth, feeding devices coöperative with 65 the front face of the platen, and a card chute extending downward and rearward below the platen.

35. In a typewriting machine, the combination of a platen carrier, a platen thereon, 70 a card container on the platen frame and overlying the platen, card feeding devices coöperative with the platen and mounted on said container, and a card chute on the frame of the machine and underlying the platen. 75

36. In a front-strike typewriting machine, the combination of a platen, a card container overlying the platen and provided with a mouth in substantial alinement with the front face of the platen, means for supporting 80 the card container in rear of the platen and also at the under side of the platen, means for ejecting the cards one at a time downward through said mouth, feeding devices coöperative with the front face of the 85 platen, and detent devices coöperative with the cards to prevent their accidental downward displacement through said mouth, the actuation of said feeding devices to feed a card downward also causing said container 90 to be pressed against the supporting means that underlies the platen.

37. In a front-strike typewriting machine, the combination of a platen, a card container overlying the platen and provided 95 with a mouth in substantial alinement with the front face of the platen, means for ejecting the cards one at a time downward through said mouth, feeding devices coöperative with the front face of the platen, 100 and detent devices coöperative with the cards to prevent their accidental downward displacement through said mouth, said detent devices comprising a pair of parallel 105 spring arms secured at the front of the card container and rearwardly projecting through slots therein.

38. In a front-strike typewriting machine, the combination of a platen, a card container overlying the platen, a chute or 110 guide underlying the platen, and feeding devices coöperative with the front face of the platen between said container and said chute.

39. In a typewriting machine, the combination of a platen, card feeding devices coöperative with the platen, and a card guiding and controlling device comprising two portions, one portion having its sides at angles to the other. 115

40. In a typewriting machine, the combination of a platen, card feeding devices coöperative with the platen, and a card chute comprising a portion secured to the top part 120 of the machine frame and extending downward under the platen and rearward to the back of the base, and a second portion or cross trough secured at the rear of the base. 125

41. In a typewriting machine, the combination of a rocking frame, means for rocking the same, a ribbon spool thereon, and pawl and ratchet devices for turning said spool when said frame is rocked. 55
42. In a typewriting machine, the combination of a key controlled rock shaft, crank arms thereon, a ribbon spool rotatable on said crank arms, and pawl and ratchet devices for turning said ribbon spool. 10
43. In a typewriting machine, the combination of a key controlled rock shaft, crank arms thereon, a ribbon spool rotatable on said crank arms, a ratchet wheel connected to said spool and supported to move bodily therewith, and a coöperative spring pawl mounted on a relatively fixed part. 15
44. In a typewriting machine, the combination of a card container, card ejecting devices, a hand controlled pressure device for the cards in said container, and ribbon feeding devices operative by said hand controlled device. 20
45. In a typewriting machine, the combination of a card container, a hand controlled follower plate coöperative with the cards in said container, ribbon feeding devices, and connections between said devices and said follower plate. 25
46. In a typewriting machine, the combination of a card container, a card follower therein, a key, connections between said key and said card follower, ribbon feeding devices, and connections between said key and said ribbon feeding devices. 30
47. In a typewriting machine, the combination of a card container, a follower therein for maintaining pressure against the pack of cards, a spring operative on said follower, a key for retracting said follower, a ribbon spool, devices for turning said spool, and connections between certain of said devices and said key. 40
48. In a typewriting machine, the combination of a card container, a card follower therein, key connections to said follower, a ribbon spool mounted on certain of said connections and provided with a ratchet, and a pawl coöperative with said ratchet. 45
49. In a typewriting machine, the combination of a card container, a card follower therein, key connections to said follower, a ribbon spool mounted on certain of said con-
- nections and provided with a ratchet wheel, and a pawl coöperative with said ratchet wheel, said pawl being mounted on said container and being independent of said key connections. 55
50. In a typewriting machine, the combination of a platen, a stencil container, means for ejecting the stencil cards from said container to the platen, a ribbon, and means for feeding said ribbon over the platen and between it and the stencil cards. 60
51. In a typewriting machine, the combination of a platen, a stencil container, means for ejecting the stencil cards from said container to the platen, a ribbon, means for feeding said ribbon over the platen and between it and the stencil cards, 65 a pressure device in said container, and hand devices for controlling said pressure device, said ribbon feeding means being automatically operative from said hand devices. 70
52. In a typewriting machine, the combination of a card container, a card follower, and an inking ribbon spool connected to said follower. 75
53. In a typewriting machine, the combination of a card container, a card follower, a ribbon spool, and means operatively connected with said follower for turning said spool axially. 80
54. In a typewriting machine, the combination of a card container, a card follower, a ribbon spool, and means operatively connected with said follower for turning said spool axially and also for moving said spool bodily. 85
55. In a typewriting machine, the combination of a card container, a card follower, a ribbon spool, means for affording movement of the ribbon during movement of the follower in one direction, and means for affording reverse movement of the ribbon during movement of the follower in the opposite direction. 90

Signed at the borough of Manhattan, city of New York, in the county of New York, 100 and State of New York, this 27th day of June A. D. 1912.
